SCRAPER

Mary C. Johnson, 2639 Kilburn, Dallas, Tex.

Filed May 21, 1962, Ser. No. 70,220

Term of patent 14 years

(Cl. D9—6)

FIG. 1 is a top perspective view of a scraper showing my new design;

FIG. 2 is a front end view thereof;

FIG. 3 is a top plan view thereof;

FIG. 4 is a cross-sectional view taken on the line 4—4 of FIG. 3; and

FIGURE 5 is a bottom plan view thereof.

My design for the scraper disclosed is characterized by the specific configuration of the smaller blade portion as shown associated with the troughed and angled handle which widens into a larger blade portion.

I claim:

The ornamental design for a scraper, substantially as shown.
